UNITED STATES PATENT OFFICE.

HUGH K. MOORE, OF BERLIN, NEW HAMPSHIRE.

METHOD AND MEANS FOR HYDROGENATING UNSATURATED COMPOUNDS.

1,184,480.

Specification of Letters Patent. Patented May 23, 1916.

Application filed October 31, 1914. Serial No. 869,689.

To all whom it may concern:

Be it known that I, HUGH K. MOORE, a citizen of the United States, and a resident of Berlin, in the county of Coos and State 5 of New Hampshire, have invented certain new and useful Improvements in Methods and Means for Hydrogenating Unsaturated Compounds, of which the following is a specification.

10 This invention has relation to the hydrogenation of oils or fats, or other like unsaturated compounds such as the esters or glycerids of the fatty acids, the fatty acids, etc., and it has for its object to provide certain improvements, not only in the process 15 of hydrogenating unsaturated compounds, but also in certain of the instrumentalities which may be conveniently used in connection therewith, so that the process may be carried on commercially in an economical 20 manner and the product placed upon the market at a reasonable cost of production.

In general, the process, in its more essential features, is set forth in my application 25 Serial No. 821,241, filed February 26, 1914, to which reference may be had for a general description thereof.

According to the process outlined in the said application, unsaturated compound 30 (which for convenience I hereinafter term "oil") is atomized by a blast of hydrogen and is caused to pass through a layer of finely divided catalytic material, preferably held upon a diaphragm which is pervious 35 to the hydrogen and oil but impervious to the catalyzing material, the result of which is that the oil is hydrogenated and the product is removed without carrying with it any of the catalytic material.

40 One of the objects of the present invention is to insure the purity of the resultant product by preventing any deposit of carbonaceous material in the diaphragm or catalyzer such as would tend to discolor the resultant product.

45 Another object of the invention is to provide for supplying the hydrogen at a predetermined temperature, free of water or other foreign substance, irrespective of 50 whether the hydrogen be that which was previously used in excess in the hydrogenation of the compound, or in the reduction of the catalyst, or whether it be drawn from its original source of supply.

55 Still another object of the invention is to provide instrumentalities for accomplish-

ing these desirable results, and to provide certain improvements in the instrumentalities themselves.

A further object of the invention is to 60 provide a body of catalyzing material of a finely divided nature in such form that it will not crack or contract and permit the oil and hydrogen to pass through without 65 coming into intimate contact with the catalytic material.

The invention has further for its object to provide other improvements which are illustrated upon the accompanying drawings, described in the following specification and pointed out in the appended 70 claims.

Referring to the accompanying drawings,—Figure 1 represents in plan view 75 diagrammatically instrumentalities which may be utilized in carrying out my improved process. Fig. 2 represents partially in section what I may term the hydrogenator; that is, the instrumentality in which the saturation of the compound is effected. Fig. 3 represents an enlarged more or less conventional view of a section of the layer of catalytic material and the diaphragm. Fig. 4 represents in section a drier which is utilized in abstracting any moisture that 80 may be therein contained. Fig. 5 illustrates a longitudinal section through the heater which is utilized for supplying to the hydrogenator the hydrogen which is employed in reducing the material to its active catalytic condition for use as a catalyst. Fig. 6 represents a form of heater, which I find 85 convenient for heating the hydrogen which is being re-used in the hydrogenation of the oil. Fig. 7 illustrates a longitudinal section through a separator which is employed for abstracting from the hydrogen, which has 90 passed through the hydrogenator, any entrained oil. Fig. 8 represents a transverse section therethrough. Fig. 9 represents a 95 section through one of the coolers which is employed for condensing moisture out of the hydrogen.

Before proceeding to describe one way in which the process may be carried out and the instrumentalities which I have illustrated as being capable of convenient employment in connection with the process, I desire to have it understood that the invention is not limited to the particular process or the particular steps which I shall describe, nor to the employment of the par- 105 110

ticular form of apparatus. I have not attempted to illustrate the exact relative sizes of the various instrumentalities or their exact locations in carrying out the process, 5 since Fig. 1 of the drawings is in the nature of a diagrammatic view in which the parts are located on the sheet of drawings where they can be seen to the best advantage. In point of actual practice, the various instrumentalities are located relatively close together and at different elevations so as to obviate the necessity of using long conduits for the hydrogen and to secure a compactness of arrangement. 10 Referring now to Fig. 1 for a general description of a way in which the process may be practised,—10 indicates what I term for convenience a "hydrogenator" in which the oil or other compound is reduced by hydrogen in the presence of a catalyst. This apparatus will be described subsequently more in detail. The oil, or other compound, which is admitted to this apparatus, is drawn from any suitable source and is supplied therefrom by a conduit 11. The hydrogen which may be obtained in any suitable way, as for instance, by the electrolytic decomposition of sodium chlorid and water, may be stored in a gasometer 12, from which 15 it is drawn as needed. The first step which is essential before the actual hydrogenation of the oil, is the reduction of the material to be used as a catalyst. This necessitates the supplying of the hydrogen at a relatively high temperature and in a condition in which it is free from moisture, oil and other impurities. To this end, I locate between the hydrogenator and the gasometer, which I may for convenience term the 20 source of supply, means for depriving the hydrogen of any entrained or dissolved moisture or other impurities. 13 indicates such means, which I may term the dehydrator, and which is supplied with any suitable hygroscopic material for absorbing the moisture. This is preferably located between the hydrogenator 10 and the tank 14, into which the hydrogen is pumped by a compressor 15 from the gasometer 12. Between the compressor and the storage tank 25 is preferably placed a cooler and condenser 16. In the storage tank 14, the hydrogen may be held at a pressure of approximately 100 pounds to the square inch. From the dehydrator the gas is supplied to the hydrogenator 10 by a conduit 17, connected to a pipe 18 which leads into the top of the hydrogenator. From the lower portion of the hydrogenator the hydrogen is led by conduits 19 and 20 to a cooler 21, and thence through a dehydrator 22 to a compressor 23, and thence to a heater 24 by which the hydrogen is heated to the desired temperature. From the latter, it is conducted by a conduit 251 to conduit 26 connected to that at

18. This much of the apparatus is utilized for the reduction of the nickel oxid or other material which is used as a catalyst. After the desired quantity of hydrogen is admitted to the upper chamber of the hydrogenator and has passed through the catalyzing material, it is heated by the heater 24 to the desired temperature and circulated again through the layer of oxid at the necessary temperature for the reduction thereof. The reduction takes place at approximately a temperature of 570° F. and hence the gas is preferably heated to a temperature between 600° F. and 650° F. or higher, if desired, to compensate for losses by radiation or otherwise. 75 80

After the material, which forms the catalyst, has been properly reduced to active condition, the oil is supplied and is atomized by a blast of hydrogen and is caused to pass with the hydrogen through the catalytic material. The gas is supplied to the hydrogenator greatly in excess of that needed for the reduction of the oil and is circulated therethrough. As pointed out in the application to which reference has already been made, and as will be subsequently described, there is in the hydrogenator preferably a diaphragm in which the catalytic material is contained, this diaphragm serving to divide the hydrogenator into two chambers, one above, and the other below the diaphragm. A suitable difference in pressure is maintained in these two chambers so that the hydrogen will be forced at high velocity through the catalytic material in the diaphragm into the lower chamber. The hydrogen, which is delivered from the lower compartment through the conduit 19, is, when the reduction of the oil is proceeding, delivered to a conduit 25 connected to that at 19. This gas, if desired, is passed through a cooler 261 like that at 16, where it is cooled sufficiently to condense the vapors and to permit the separation of the resulting entrained oil in an oil separator which is indicated at 27. The gas, which is thus freed from the oil, is delivered to the dehydrator or drier 28 which removes any remaining moisture and any entrained oil, if there be any. From the dehydrator or drier the hydrogen is pumped by a compressor 29 (preferably driven by a variable speed motor, not shown) through a heater indicated as a whole at 30, and thence it passes through a conduit 31 to the conduit 26 by which it is again delivered to the hydrogenating apparatus. 90 95 100 105 110 115 120 125 130

For the atomization of the oil, it is necessary that it be sprayed into the hydrogenating apparatus by gas under a higher pressure than that which is in the upper compartment of the hydrogenator; and hence, for this purpose, I utilize a relatively small compressor 32 which as shown may 130

draw gas from the main outlet 25 through a conduit 33 and delivers it through a conduit 34 to the nozzle. The volume of gas passed through this compressor is relatively small as compared with that which passes through the main compressor 29, and, since this gas is passed back into the hydrogenating apparatus with but little loss of heat, I do not find it practically necessary to use a heater and consequently there is no necessity for the employment of an oil separator or drier or cooler. If desired, the intake of the compressor might be connected with the pipe 26 instead of the pipe 25 to reduce the work of the compressor 32.

These various instrumentalities, which I have referred to thus briefly, are more especially desirable for use in connection with the hydrogenation of oil for edible purposes where the discoloration of the product is highly objectionable.

I shall now proceed to describe in detail the various instrumentalities to which I have briefly referred, but in so doing, as I have already pointed out, I desire it to be understood that the invention is not limited to the use of such particular instrumentalities, although I find them to be desirable for accomplishing the purposes for which they are utilized. I have not complicated the drawings by showing all of the various valves and pipes and fittings that may be used to control the flow of oil and hydrogen, but it will be understood that they are used wherever necessary.

I will first describe the hydrogenating apparatus. This is indicated as a whole at 10, and, as illustrated comprises a large shell or casing, across which is placed a grid 40 consisting of a plate provided with numerous rows of perforations. The upper surface of the plate is preferably provided with intersecting V-shaped grooves 41, the bottoms of which communicate with the apertures 42. Thus the upper surface of the plate is provided with a series of rows of projections 43 of pyramidal form. This grid is utilized for supporting the diaphragm, and upon it is placed a sheet of heavy steel wire cloth 44 which is preferably rolled to flatten the exposed surfaces of the wires. The rolling of the cloth prior to its using stiffens it and securely interlocks the wires together. Upon the wire cloth 44 is placed a second cloth 45 formed of much finer wire and with much smaller mesh. These three elements, to wit, the perforated grid and the two layers of wire cloth, constitute a support for the diaphragm, and the construction and arrangement is such that the diaphragm is supported at very closely adjacent points where it comes in contact with the layer of fine wire cloth so as to prevent its yielding or breaking. Upon the cloth 45 is placed a sheet 46 of

asbestos paper or its equivalent which is pervious to oil and hydrogen but impervious to the catalytic material. This catalytic material is in a finely divided state and may be formed from any of the usual metals such as palladium, platinum, nickel, etc.

Assuming that the nickel is to be used as a catalyst, the oxid in a finely divided condition may be thoroughly mixed with long or stringy asbestos fiber, and a layer thereof is placed upon the sheet 46, as indicated at 47. A second sheet 48 of asbestos may be then placed upon the layer and a second layer of asbestos fiber and nickel oxid laid thereon as indicated at 49. To hold the layers in place, there is located above them a sheet 50 of fine wire cloth. If desired, a sheet of asbestos, not shown, may be interposed between the top layer of catalytic material and the wire gauze 50. The margins of the asbestos 48 and the wire gauze 50 may be turned upwardly, as shown in Fig. 2, and clamped against the inner wall of the casing by a metallic ring 51, the expansion of which is preferably a little greater than that of the casing so as to prevent the formation of cracks between the diaphragm and the wall of the casing. The grid and the diaphragm are supported upon hollow cross bars placed in the lower portion of the casing, as indicated in dotted lines at 52, to divide the casing into two compartments.

I have stated that the layer of catalytic material contains in mixture therewith long fibered asbestos. This is merely a mechanical mixture, the asbestos being utilized to prevent the layer of catalytic material from cracking, very much as hair has been used in plaster for the same purpose. Only a very small quantity of the fibered asbestos is necessary for this purpose. After the diaphragm is formed, with nickel oxid, for instance, for providing the active material, the hydrogen at a high temperature is passed therethrough to reduce it to its active condition. The hydrogen from the pipe 34 is delivered to the rotary pipe 54 which extends down into the casing and which is driven by a worm wheel 55 and worm 56 supported upon a frame 57. The pipe 54 is provided with a nozzle 58 for directing the blast of hydrogen against the oil which is delivered from the nozzle 59, the latter being connected to a pipe 60, to which is coupled the pipe 11 leading from the source of oil supply. The two nozzles 58 and 59 are in close proximity, so that, as the oil issues from the nozzle 59, it is blown across a portion of the upper surface of the diaphragm. The finely divided oil and hydrogen pass through the layer of catalytic material and the oil is saturated or reduced by the hydrogen. As the nozzles revolve, the spray is directed toward successive portions of the diaphragm, the excess hydrogen passing

through the remaining portions and revivifying the catalyzing material. As considerable hydrogen in excess is required, it is supplied to the casing through the conduit 18. The hydrogenated product is continuously removed from the lower portion of the casing by the eduction pipe 62. The unused hydrogen, which passes through the diaphragm, is carried out through pipes 63 of 10 which there may be as many as desired, these pipes being connected to the pipe 19 in Fig. 1. Said pipes are arranged above the bottom of the casing below the diaphragm and are provided on the under portions of their peripheries with numerous holes or perforations leading to the interior thereof for the entrance of the gas. For the protection of the pipes from the hydrogenated product, aprons or shields 64, which are substantially 15 U-shaped in cross-section, are placed upon the pipes as shown, so that the hydrogenated product dripping down will not be entrained to any considerable extent in the outflowing gas. For the purpose of maintaining the 20 temperature within the casing at the proper point, the casing may be encircled by a series of pipes 65 connected to the manifolds 66, 67, superheated or high pressure steam being supplied to the former and conducted away 25 from the latter by suitable conduits. These pipes, as well as the entire exterior of the casing, are completely covered by one or more layers of insulating material such as magnesia or other suitable substance to prevent 30 the loss of heat by radiation. The pressure of the atmosphere of hydrogen above the diaphragm is maintained at a point considerably higher than the pressure of the atmosphere below the diaphragm to 35 insure the passage of the hydrogen through the diaphragm at a high velocity, and the hydrogen which is blown in through the nozzle 58 is at a still higher pressure in order 40 to form the atomized blast.

45 One of the difficulties that I have met with practically in the operation of an apparatus of this character having a diaphragm of large area has been due to the occasional cracking of the catalytic layer and also due 50 to the expansion of the casing which forms cracks or spaces at the outer edges of the diaphragm, through all of which cracks and spaces the hydrogen escapes into the lower compartment, thereby permitting some of 55 the oil to pass through without being reduced, and so reducing the pressure above the diaphragm that the gas will pass therethrough in only limited quantities. I have overcome this difficulty by incorporating 60 with the layer of catalytic material long-fibered asbestos, as hereinbefore explained, which I find prevents the formation of cracks. The difficulty, due to the expansion 65 of the casing, has been overcome by the provision of the ring 51 which clamps the

margins of the portions of the diaphragm against the outer shell. This ring expands coincidently with the shell so as to hold the edges of the diaphragm thereagainst, said ring permitting a slipping of the edge 70 of the diaphragm past it as the ring expands without causing a tearing or breaking of the diaphragm. In actual practice, the ring may be covered over by a layer of the catalyzing material at the outer edge of the 75 diaphragm. Due to the pressure upon the diaphragm, it is necessary that it should be rigidly supported and yet that it should be supported in such way as not to obstruct the flow of the gas and the hydrogenated product through it. I accomplish this by the grooved and perforated grid which may be made of such thickness as to withstand the pressure, and by the use of one or more layers of wire cloth placed thereon. Practically 80 I employ two layers, the lower one of heavier wire cloth and the upper one of a finer mesh, in order that the asbestos may not be forced 85 into the meshes.

Cooler and condenser.—Any suitable apparatus for removing moisture from the gas, as during the reduction of the catalyst, may be utilized, but I have shown in Fig. 9 an apparatus which I utilize at either 16 or 261 in Fig. 1. This apparatus may consist 90 of an ordinary condenser. Water is admitted to the lower chamber 70, and, passing through the tubes 71 into the upper chamber 72, is conducted away. The gas is admitted to the space between the tubes 100 by the pipe 73 and is conducted therefrom by the pipe 74. As the cooling medium, I may use ordinary river water at seasonable temperature. In the case of the cooler at 16, in Fig. 1, the greater part of the moisture contained in the gas is condensed and removed. In the case of the cooler 261, however, not only is a portion of the contained moisture (if there be any) removed, but also a large portion of the oil which is 110 dissolved in the gas is condensed and removed therefrom or put in the condition of entrainment, so that it may be subsequently removed by the oil separator. In lieu of the condenser shown, however, any other 115 suitable form may be employed.

Oil separator.—For the purpose of removing from the hydrogen that has passed through the hydrogenating apparatus the oil, which has been placed in condition for 120 entrainment, I employ an oil separator, and to this end I may use an apparatus such as shown in Figs. 7 and 8. This separator consists of an elongated cylinder 80 having heads 81, 81, secured on the ends thereof. Within the cylinder is placed a number of disks 82 which are strung upon a rod 83 and spaced apart by sleeves 84. These disks are provided with numerous perforations, the perforations of each disk being out of alignment 125 130

ment with the perforations of the two adjacent disks. Leading from the space between each pair of disks, there is a trapped outlet pipe 85 communicating with a manifold 86. The gas and its entrained oil is admitted at one end through the pipe 87, and the gas freed from the oil is admitted through a pipe 88 at the other end.

As the gas with the entrained oil passes at high velocity through the separator, the oil comes in contact with the plates and forms globules thereon which gradually run down and are carried away through the pipes 85 to the manifold 86. I have shown this form of separator which I have found to be satisfactory for the purpose, but any other suitable form may be utilized in lieu thereof.

The dehydrator.—It is of great importance, not only in the hydrogenation of the oil but also in the reduction of the catalytic material, completely to remove, so far as possible, all moisture from the hydrogen, for, if the moisture remains in the gas, it will be broken up in the heater and the free oxygen and other oxygen compounds will injure the catalyzing material. Consequently I employ what I term a dehydrator, such as shown in Fig. 4. This may consist of a closed casing 90 provided with staggered shelves 91, upon which is placed a quantity of dehydrating or hygroscopic material such as fused calcium chlorid or the like. The gas is admitted to the lower portion of the casing through a pipe 92, and following a tortuous path upwardly passes over and in contact with the dehydrating material and is finally emitted from the pipe 93. I preferably form the shelves 91 with numerous small apertures through which the gas may pass upwardly through the layers of dehydrating material thereon, and inasmuch as the dehydrating materials are usually deliquescent, the perforations in the shelves permit the resulting liquid gradually to flow down so as to be discharged through the valved drain pipe 94. By fusing off the water, the dehydrating material can be reused. In the commercial practice of my process, I have found an apparatus such as just described to be satisfactory, but any other suitable form of dehydrating apparatus may be utilized in lieu thereof. I preferably employ fused calcium chlorid for the reason that it has an affinity for oil as well as for water, and, if any oil escapes from the separator, it is taken up and removed in the dehydrator.

The heaters.—In the reduction of the catalytic material, it is necessary that the gas should be heated to a relatively high heat; whereas, for the reduction of the oil, the gas need not be heated to such a high temperature, although the temperature will be regulated according to the product to be ob-

tained, say from 175° F. to 480° F., as I have already explained; and I therefore preferably employ two forms of heater, each especially designed for its particular purpose. In raising the gas to its highest temperature for the reduction of the catalyzer, which operation takes but a relatively short time, say from 3 to 6 hours, and in which there is little or no possibility of oil having been entrained with the gas due to the gas having been drawn from its original source of supply, I find it possible to use the heat generated by electrically resistant materials with which the gas may come directly in contact, thus enabling the gas to be quickly raised to any desired high temperature. It is necessary that such resistant materials be employed as will not be acted on by the hydrogen at the high temperatures to which it is raised. It is possible to utilize for this purpose pieces of carbon such as the carbon pencils used in arc lamps. These pencils are broken up into relatively short lengths and the entire mass is confined within a suitable holder. An electric current of high amperage and low voltage is passed through them coincidently with the passage of the hydrogen through the interstices of the mass. In Fig. 5 of the drawing, I have illustrated a heater in which the mass of carbon rods 100 is confined within a tube 101 formed of fire clay, magnesia or equivalent material. Into each end of the tube there is inserted a block 102 of Acheson graphite, the periphery of which is grooved or slabbed off so as to permit the passage of gas thereby, while holding the resistant material in place. The blocks 102 are held in place by metallic holders 103, against which bear the ends of screws 104. These screws are passed through cylinder heads 105 insulated from but bolted to a cylinder 106. The cylinder and the heads may be formed of metal. The shell or casing thus formed is completely inclosed within a covering 107 of heat-insulating material. Between the tube 101 and the cylinder 106 is placed a mass 108 of heat-resistant material, such as powdered fire brick or the like, which is sintered together to form a solid mass after it is put in place. The gas to be heated is admitted through a pipe 109 into the space between the filler 108 and one of the cylinder heads, and is conducted from the heater by a pipe 251 leading to the pipe 26. Connected to the heads 105 are terminals 111 of conductors leading from a secondary coil of a transformer indicated at 113 in Fig. 1. A transformer of suitable character is employed for the purpose of delivering a current of high amperage and low voltage; for instance, a current of 2400 amperes at a maximum potential of approximately 50 to 55 volts. The current, in passing from one of the blocks 102 to the other through the mass of resistant ma-

terial, heats the latter at their multitudinous points of impingement to a high temperature, so that the gas, in passing through the mass, is heated to a temperature necessary for the reduction of a catalytic material. I use a current of low voltage and high amperage in order to prevent the formation of arcs such as would cause the hydrogen to react with the carbon, with the formation of 5 acetylene, while at the same time the resistant material is heated to a high temperature. The gas possesses low powers of conductivity, but, by being passed through the interstices formed between the carbon rods 10 which are packed together, is heated with but little loss of heat. It is possible to control the temperature of the gas in either of two ways; first, by varying the flow of the gas through the heater, and, secondly, by increasing or decreasing the resistance in the 15 circuit. The resistance may be varied by the adjustment of the screws 104. By packing the resistance material more closely together, a greater flow of current is permitted 20 with a consequent rise in temperature of the resistant material; whereas, by partially unscrewing the screws so as to reduce the pressure of the pieces of resistant material upon each other, the resistance to the passage of 25 the current will be increased, and the heat generated will be correspondingly diminished. This heater, as previously explained, is preferably used only for raising the temperature of the gas which is utilized for the 30 reduction of the catalyzing material, where there is no possibility of oil passing through 35 with the gas.

For heating the hydrogen, which has already been used in the hydrogenator, to 40 a relatively lower temperature which is necessary for the reduction of the oil, I may employ a heater such as shown in Fig. 6, in which case the gas is heated by conduction as it is passed through a series of pipes 45 by heating the pipes themselves. In Fig. 6, I have shown such a heater, which consists of a manifold 120 to which the gas is supplied from the pipe 121. From the manifold 120 a series of pipes 122 lead to a manifold 123 connected with the pipe 31, see 50 Fig. 1. Around each pipe 121 there is one or more resistance coils 124 inclosed within a layer 125 of insulating material. These pipes and the manifold 123 are located within 55 a casing 126 containing a packing of non-conducting material 127. I may use for this purpose magnesium and asbestos fiber or any other equivalent substance. The resistance coils are connected with the secondary of 60 a transformer 128 so constructed as to provide a potential of 110 volts, which is the ordinary lighting circuit. The gas, in passing through the pipes from one manifold to the other, is heated to the desired temperature. Any suitable form of regulating 65

device for the resistance coils may be utilized to regulate the temperature of the gas. It is possible to use in lieu of an electric heater a steam heater, although I prefer the electric heater as it prevents any possibility of 70 the access of steam to the gas by leakage.

I have found the heaters which I have described to be satisfactory, but it will be understood that other forms of heating apparatus for the hydrogen may be utilized 75 in lieu thereof.

I have thus described in detail the various instrumentalities which I recommend for carrying out my process in order that persons skilled in the art may have the advantage 80 of the knowledge I have gained in the hydrogenation of unsaturated compounds, and in order that users of the process may be guided in the selection or construction of apparatus suitable for the purpose. 85

In my previous application I have pointed out the desirability of securing a fine division of the oil prior to its reduction by the hydrogen, and I also explained a theory I have formed of the reaction that takes place 90 during the reduction of the unsaturated compound. Later developments have lead me to believe that the catalytic material does not form the simple hydrid which I suggested as an example in the specification of 95 my application. While these later developments have served to confirm my belief that unstable hydrids are formed, yet I am now inclined to the opinion that these hydrids are more complex, such as would be represented by the formula Ni_3OH_x , where " x " may indicate a variation within considerable limits. Quite irrespective of my theory, however, it is unquestionably the fact that, by my process, unsaturated compounds may 105 be commercially reduced by a continuous process and to the desired point of saturation, and the catalyst may be revivified when the same becomes sluggish or inactive 100 by passing the hydrogen therethrough. 110

So far as my work has gone, I have been unable to determine the limits of indestructibility of a given quantity of the catalyst, when revivified from time to time as directed in my earlier application. While the 115 asbestos layers of the diaphragm occasionally require renewal, due to their being plugged by albuminous matter, yet I have discovered no deterioration of the catalytic material itself. In this connection I may 120 refer to the fact that I have herein suggested the employment of a compressor driven at vairable speeds, so that, as the asbestos portion of the diaphragm gradually becomes increasingly resistant to the 125 passage of the hydrogen and the reduced product therethrough (on account of the accumulation of albuminoids or other substances), the pressure and volume or weight of gas delivered from the compressor may 130

be correspondingly varied. In explanation, there is a physical and chemical law which may be stated roughly as follows:—In a gaseous reaction tending to reduce the number of molecules present, the reaction is directly proportional to the pressure. In the present case, notwithstanding the oil or other compound may be a liquid, I believe the reaction to be gaseous, in view of the 5 fine atomization of the compound. Hence, in the hydrogenation, I maintain the hydrogen under high pressure. As the diaphragm clogs, which would naturally cause a gradual increase in the pressure above the 10 diaphragm (assuming the delivery of the hydrogen from the compressor to be at a constant pressure and volume), it is desirable to reduce the weight of hydrogen being delivered from the compressor, so as to 15 maintain the hydrogen above the diaphragm at the working pressure which has been found desirable to secure a uniformity of product, and hence the compressor is driven 20 at slower speed.

25 Having thus described a way of practising my invention and forms of apparatus which may be employed therewith, without attempting to set forth all the ways in which said invention may be practised or all the 30 forms of apparatus useful therewith, what I claim is:

1. The herein described process which consists in circulating hydrogen in excess into contact with oil through a diaphragm 35 containing a catalyzer to reduce the oil, and cooling the unused excess hydrogen for the condensation and removal of contained vapor.

2. The herein described process which 40 consists in circulating hydrogen in excess into contact with oil through a catalyzer contained in a diaphragm pervious to the oil and gas but impervious to the catalyzer to reduce the oil, condensing the vapors contained in the excess unused hydrogen, and 45 separating from such hydrogen the entrained moisture and oil.

3. The herein described process of hydrogenating oil which consists in passing 50 hydrogen and oil under pressure through a catalytic diaphragm pervious to oil and hydrogen and impervious to the catalytic material, and decreasing the weight of the hydrogen being fed as the resistance to the 55 passage of the hydrogen therethrough increases, so as to preserve a uniformity of pressure on the diaphragm.

4. The herein described process which 60 consists in circulating hydrogen in excess into contact with oil and a catalyst to reduce the oil, condensing and removing moisture and entrained oil from the unused excess hydrogen, heating said hydrogen, and reusing such hydrogen for the reduction of more 65 oil.

5. The herein described process which consists in circulating hydrogen in excess into contact with oil and a catalyst to reduce the oil, cooling the unused hydrogen to condense vapors, removing moisture and entrained oil from such cooled hydrogen, then heating the hydrogen and then reusing the same for the reduction of more oil. 70

6. The herein described process which consists in circulating a volume of hydrogen 75 through a mass of catalytic material, atomizing a stream of oil by a separate stream of hydrogen and passing the atomized oil through the catalytic material.

7. The herein described process which 80 consists in atomizing a stream of oil by a stream of hydrogen on one side of a pervious diaphragm containing a catalyzer, supplying an additional stream of hydrogen on the same side of said diaphragm, and passing the atomized oil and excess hydrogen through said diaphragm into contact with said catalyzer, and withdrawing the hydrogenated product. 85

8. The combination with a hydrogenating apparatus, and a support therein for a body of catalytic material, of means for circulating gas through said apparatus and catalytic body for the reduction of the catalyst, including a cooler for condensing the 90 contained moisture in the gas, means for dehydrating said gas, a compressor, and a heater for the gas. 95

9. The combination of a hydrogenating chamber, means therein for supporting a 100 layer of catalytic material, means for purifying, heating and circulating gas through said hydrogenating chamber and catalytic material to reduce such material, and separate means for purifying, heating and circulating gas in excess through said chamber and catalytic material for the hydrogenation of an unsaturated compound. 105

10. The combination with a hydrogenating apparatus comprising an atomizer for 110 hydrogen and oil, and an independent inlet for hydrogen, of means including a pump for forcing hydrogen discharged from said apparatus through said atomizer, and means connected with said inlet for circulating hydrogen through said apparatus, including a pump, means for depriving the hydrogen of contained vapor and oil, and a heater for the hydrogen. 115

11. The combination with a hydrogenating apparatus of means for circulating excess hydrogen therethrough comprising a condenser, an oil separator, a dehydrator, a compressor, a heater, and conduits connecting the same so that the hydrogen passes 120 through the same in the order named.

12. The combination with a hydrogenating apparatus having oil and hydrogen nozzles for atomizing the oil, of a compressor 125 for forcing hydrogen through its appro- 130

priate nozzle, and a compressor for forcing hydrogen in excess into said hydrogenator.

13. The combination with a casing having a layer of catalyzing material therein, and 5 nozzles therein for atomizing oil by a blast of hydrogen, of a compressor for delivering hydrogen under high pressure to the atomizer nozzle, and a compressor for delivering excess hydrogen under lower pressure to 10 said casing.

14. A diaphragm for oil-hydrogenating apparatus, comprising a layer of material impervious to a finely divided solid but pervious to hydrogen and oil, and a layer thereon consisting of a catalyst capable of reducing oil with hydrogen and having mechanically mixed therewith or incorporated therein a fibrous material for preventing the formation of cracks.

15. The combination with a casing, of a grid therein, said grid being provided with apertures, and with intervening projections on its upper surface, a layer of coarse wire cloth resting on said projections, a superposed layer of fine wire cloth, and a catalytic diaphragm resting thereon.

16. The combination of a casing, a diaphragm therein provided with catalytic material, means for supplying oil and gas to the interior of the casing above the diaphragm, an outlet below the diaphragm for the hydrogenized product, and a transverse

reduction pipe for the hydrogen below the diaphragm, having openings in its under portion.

17. The combination of a casing, a diaphragm therein provided with catalytic material, means for supplying oil and gas to the interior of the casing above the diaphragm, an outlet below the diaphragm for 40 the hydrogenized product, a transverse reduction pipe for the hydrogen below the diaphragm, having openings in its under portion, and a shield or apron on said pipe, substantially for the purpose described.

18. The combination with a casing, of a diaphragm therein containing a catalyst capable of reducing oil with hydrogen, and an expansible ring clamping the margin of the diaphragm against the inner wall of the 50 casing.

19. The combination with an apparatus for the hydrogenation of oil, of a heater, a dehydrator having hydroscopic material, and means for forcing hydrogen first 55 through said dehydrator and then through said heater to said apparatus.

In testimony whereof I have affixed my signature, in presence of two witnesses.

HUGH K. MOORE.
